UNITED STATES PATENT OFFICE.

HERBERT JEFFREY DYKE, OF ST. LAMBERT, QUEBEC, CANADA.

RAILWAY SWITCH.

Application filed October 18, 1926. Serial No. 142,399.

My invention relates to certain new and useful improvements in railway switches and more particularly to slide plates, heel plates and turn out plates for supporting the stock rails in an inwardly inclined position, and supporting the closure rails and switch rails in correct positions relative to the inclined stock rails.

It is well known to those familiar with railway construction that tie plates having inclined top bearing surfaces are now in general use, the inclined surfaces being so arranged to give the rail an inclination towards the centre of the track, but the rails used in the construction of switches are still carried on flat plates giving no inclination. This causes undue twisting strains on the rails where they leave the inclined plates and are carried on the flat plates, and the rails are not properly supported on the flat plates for a considerable distance.

My invention is designed to overcome these conditions and to provide switch slide plates to support the stock rails with the correct inward inclination, and carry the switch rails in relation thereto; to provide heel plates and turn out plates for gradually bringing the closure rails to the correct inward inclination, and for carrying the stock rail correctly inclined.

This construction brings the switch in line with modern practice of inclining the rails, provides suitable plates on which to carry the rails, and obviates any unnecessary strain being put on the rails and makes an improved track layout.

In order that those skilled in the art to which my invention pertains shall know how to make and apply the novel features of construction and combination of parts, I will proceed to fully describe them.

In the accompanying drawings:

Fig. 1 is a plan of a switch layout showing the location of the novel plates used to support the stock rails, closure rails, and switch rails.

Fig. 2 is an elevation of the slide plates located at places marked 2 on Fig. 1, which are used to support the stock rails in an inwardly inclined position, and the switch rails in a vertical position, the switch rail sliding transversely on the slide plate while the stock rail is fixed. A rail brace as shown is also carried on this plate to support the stock rail laterally.

Fig. 3 is a plan view of the slide plate shown in Fig. 2.

Fig. 4 is an elevation of the slide plate located at places marked 4 on Fig. 1 and is used to support the stock rails in a fixed inwardly inclined position, and the switch rails in a vertical position, the switch rail sliding transversely on the slide plate.

Fig. 5 is a plan view of the slide plate shown in Fig. 4.

Fig. 6 is a cross sectional view showing the shape of the slide plate on line E—E, Fig. 3, and line F—F Fig. 5.

Fig. 7 is an elevation of a heel plate located at place marked 7 on Fig. 1, for carrying the stock rails in an inwardly inclined position, and the closure rails in a vertical position.

Fig. 8 is a plan view of the heel plate shown in Fig. 7.

Fig. 9 is an elevation of the turn out plates located at places marked 9, on Fig. 1, to support the stock rail in an inwardly inclined position and the closure rails in a less inwardly inclined position.

Fig. 10 is an elevation of the turn out plates located at places marked 10 on Fig. 1 to support the stock rails in an inwardly inclined position and the closure rails in a less inwardly inclined position, but at a greater inclination than shown in Fig. 9.

Fig. 11 is an elevation of the turn out plates located at places marked 11 on Fig. 1 to support the stock rails in an inwardly inclined position, and the closure rails in a less inwardly inclined position, but at a greater inclination than shown in Fig. 10.

Fig. 12 is an elevation of the turn out plates located at places marked 12 on Fig. 1 to support both the stock rails and closure rails at the same inwardly inclinations.

Fig. 13 is a plan view of the turn out plate shown in Fig. 12.

Fig. 14 is an elevation of an alternative slide plate which may be used instead of slide plate shown in Figs. 2 and 4, and may be used at places marked 2 and 4 on Fig. 1. The slide plate supports the stock rail in an inwardly inclined position and a rail brace outside of same, the lateral pressure being taken wholly by the rail brace. The switch rail is carried in a vertical position and slides on the plate.

Figure 15 is a plan of Figure 14.

The slide plates Figs. 2 and 4 can be used.

on either side of the switch, i. e. for both stock rails and switch rails, but the heel plates and turn out plates must be made right hand and left hand. For convenience plates used on the right hand side of the switch are shown only.

Similar reference numerals indicate like parts in the several figures of the drawings.

In Fig. 1 is indicated a lay-out of a standard railway switch. Outside of the points A. D. the rails are carried on standard inclined tie plates. Between A. and B. all the rails are carried on novel slide plates 2 and 4., which are shown enlarged in Figs. 2. and 4. Between B and C. are located the novel heel plates 7. which are shown enlarged in Fig. 7. and between C. and D. the rails are carried on the novel turnout plates 9. 10. 11. and 12. all shown enlarged in Figs. 9. 10. 11. and 12.

All the tie plates are carried on usual ties, and fastened in the usual manner by spikes or the like. The drawing Fig. 1., is diagrammatic only, and more or less ties and plates may be used for each switch layout as may be required.

In Fig. 1. the stock rails 3. 3^a. are carried in an inwardly inclined position towards the centre of the track throughout, the switch rails 5. 5^a. are carried in a vertical position, and the closure rails 6. 6^a. join the switch rails at B. in a vertical position, and are gradually turned over to an inwardly inclined position by means of the plates 9. 10. 11. and 12., until they are same inclination as the stock rails 3. 3^a.

In Figs. 2. and 3. are shown the novel slide plates 2. on which is supported the stock rails 3. 3^a. and the switch rails 5. 5^a. The slide plate 2. is provided with a raised surface 13. on which the base of the switch rails 5. 5^a. slide, and is so arranged to bring the top of the switch rails 5. 5^a. slightly above the stock rails 3. 3^a. at all points where the switch rails 5. 5^a. are full height as shown in Fig. 4. at G. An inclined seat 8. is arranged to support the stock rails 3. 3^a. at a definite inclination towards the centre of the track, the flange of the stock rails 3. 3^a. abut against the edge 20. of the slide 13., and against a stop 15. integral with the plate 2. an extension 16. is provided to seat a rail brace 18. whose outer edge abuts against a second stop 17 also integral with the plate 2. The rail brace is held in place by means of spikes 19. which passes through same and holes 19^a. in the plate 2. Holes 19^b. are provided for spiking the inside of the plate 2. to the ties, and holes 19^c. are also provided in a limited number of plates 2. for spiking the switch rails 5. 5^a. against the stock rails.

In Figs. 4. 5. and 6. a slide plate 4. is shown which is very similar to plate 2., but is without provision for seating a rail brace. Plate 4. has a raised surface 22. for carry-

ing the switch rails 5. 5^a. an inclined seat 21. for supporting the stock rails 3. 3^a., a stop 23. against which the flange of the stock rails 3. 3^a. abut, and slots 19^d. and hole 19^b. for spiking plate to ties.

Fig. 6. shows a cross section of plates 2. and 4. at sections EE. and FF.

Figs. 7. and 8. show the novel heel plate 7. in which an outside recess 24 is cut having an inclined seat to support the stock rails 3. 3^a. in an inwardly inclined position similar to plates 2. and 4. the switch rails 5. 5^a. are joined to the closure rails 6. 6^a. on plate 7. by means of standard angle bar joint plate 25. and bolts 26. the ends of the switch rails and closure rail being supported in slot 27. cut in plate 7. with a flat seat. Holes 28. are arranged through the plate 7. for spiking same to ties. The difference in height between the stock rails 3. 3^a. and the switch and closure rails 5. 5^a. 6. 6^a. is shown at G. and is the same as in Fig. 4.

As the stock rails and closure rails gradually diverge, and as the heights of these rails are different, and further the closure rails are vertical and must be given an inwardly inclination in conformity with the stock rails I use a series of novel turn out plates, 9. 10. 11. and 12., Figs. 9. 10. 11. and 12. to accomplish this purpose.

It is usual when any rail is required to be higher than the mean height of track, to run off this extra height gradually over a number of ties, and since the height G. Fig. 7. has to be run off I arranged for this in my novel turn-out plates 9. 10. 11. and 12. Further since the closure rails 6. 6^a. are vertical over heel plate 7. and at a like inward inclination at D. to the stock rails 3. 3^a. I also arrange my novel turn out plates 9. 10. 11. 12. with inside seats of varying inclinations to make this change gradually over a number of plates, and although for convenience I have chosen four plates, I may use a greater or lesser number as may best suit various types of switches.

In Fig. 9. the novel turn-out plate 9. is arranged with a slot 29. having an inclined seat of sufficient width to just fit the base of the stock rails 3. 3^a. and hold them in an inwardly inclined position, and of such inclination to line up with the inclined seats of the slide plates 2. and 4. and heel plates 7. and a second slot 30 having an inclined seat of just sufficient width to fit the base of closure rails 6. 6^a. The seat of slot 30. however, is slightly higher than the seat of slot 29. and this difference in height is such that G. 3. is three quarters G. and the rate of inclination of seat of slot 30. is one quarter the inclination of seat of slot 29.

In Fig. 10. the novel turn out plate 9. is arranged with a slot 31. having an inclined seat of sufficient width to just fit the base of stock rails 3. 3^a. and hold them in an

inwardly inclined position equal to the inclination of plates 2. 4. 7. 9. and a second slot 32. having an inclined seat of just sufficient width to fit the base of closure rails 6. 6^a., the difference in height between the stock rails and closure rails G². being one-half G. in Fig. 7. and the rate of inclination of the seat of slot 32. is one-half the inclination of seat 31.

- 10 In Fig. 11. the novel turn-out plate 11. is arranged with a slot 33. similar to and having the same inclination and purpose as slots 29. and 31., Figs. 9. and 10. and a second slot 34. similar to and having the same purpose as slots 30. and 32. Figs. 9. 10. but with the difference in height G¹. one quarter G. Fig. 7. and the rate of inclination of slot 34. three quarters the inclination of slot 33.
- 20 In Fig. 12. the novel turn-out plate 12. is arranged with two slots of equal height and inclination, the slot 35. carrying the stock rails 3. 3^a. and the slot 36. carrying the closure rails 6. 6^a., the inclinations being equal to the inclinations of slots 29. 31. 33. Figs. 9. 10. 11.

Fig. 13. is a plan of Fig. 12. and shows slot 36. on an angle with slot 35., the holes 37. are arranged for track spikes for fastening the plates to the ties. Fig. 13. also serves as a plan for Figs. 9. 10. 11. except that the distance between the two slots vary for each plate 9. 10. 11.

In Figs. 14. and 15. is shown an alternative type of novel slide plate in which the stock rails 3. 3^a. are supported on an inclined seat 40. with the inside rail base edge abutting against the edge 43. of raised slide 39. The inclined seat 40. ends at a stop 41. integral with the plate 14. which abuts against a rail brace 38 and holds same against lateral movement. Spike holes are arranged at 42. for fastening the plate to the ties. The base of the switch rails 5. 5^a. slide on slide 39.

Having thus described my invention what I claim is:

1. A railway switch using flat bottom rails having in combination inwardly inclined stock rails and closure rails with vertical switch rails.
2. A railway switch having rail supporting plates by means of which the stock rails are supported in an inclined position, the switch rails in vertical position, and the

closure rails in a position gradually changing from a vertical position to an inclined position.

3. A slide plate for railway switches having an inclined seat to take a stock rail, 60 a raised horizontal slide to carry the base of a switch rail, a stop to hold base of stock rail in position, an extended inclined seat to support a rail brace, an outside stop to prevent lateral movement of said rail brace, 65 and holes for fastening spikes.

4. A slide plate for railway switches having a raised horizontal slide for carrying the base of a switch rail, an inclined seat to take a stock rail and rail brace, a stop 70 to prevent lateral movement of the rail brace and holes for fastening spikes.

5. A slide plate for railway switches having an inclined seat to take a stock rail, 75 a raised horizontal slide to carry the base of a switch rail, a stop to hold base of stock rail in position, and holes and slots for fastening spikes.

6. A heel plate for railway switches having a recess with an inclined seat for 80 carrying a stock rail, and a recess having a horizontal seat for carrying the ends of a switch rail and closure rail where they are joined together, and holes for fastening spikes. 85

7. A double tie or turn-out plate for railway switches having a recess with an inclined seat for carrying a stock rail, and a second recess having an inclined seat at a different inclination and height to the first 90 recess, and holes for fastening spikes.

8. A double tie or turn-out plate for railway switches having two recesses with inclined seats for carrying a stock rail and a closure rail at the same height and inclination, and holes for fastening spikes. 95

9. In a double tie or turn-out plate for railway switches, a series of said plates in which outside recesses with inclined seat are kept in same relative position to carry 100 a stock rail, but the inside recess with its seat is varied both in height and inclination to gradually turn a closure rail from a vertical position to an inclined position, and from a height higher than stock rail level to 105 same level as stock rail.

In testimony whereof I offer my signature.

HERBERT JEFFREY DYKE.
